Charles J. Klein, Inventor
By his Attorney
Raymond G. St. L. Kelly.

UNITED STATES PATENT OFFICE.

CHARLES J. KLEIN, OF NEW YORK, N. Y.

PUSH-BUTTON.

SPECIFICATION forming part of Letters Patent No. 757,203, dated April 12, 1904.

Application filed November 14, 1902. Renewed February 23, 1904. Serial No. 194,882. (No model.)

To all whom it may concern:

Be it known that I, CHARLES J. KLEIN, a citizen of the United States, residing at New York, county of New York, and State of New York, have invented certain new and useful Improvements in Push-Buttons, of which the following is a specification.

This invention relates to electrical push-buttons; and it has for its object to provide an improved device of this class which will be superior in point of simplicity and inexpensiveness in construction and general efficiency and durability.

In carrying out my invention I provide a push-button in which the circuit-wires are firmly held in position for direct contact with the circuit-closing element, the necessity of binding-posts and independent contact-terminals being thus obviated.

In the drawings which form part of this specification, and in which corresponding parts in the several figures are denoted by the same reference characters, Figure 1 is a detail longitudinal sectional view of a push-button embodying the invention. Fig. 2 is a detail transverse sectional view taken upon the line *y* *y*, Fig. 1, and looking in the direction of the appended arrow. Fig. 3 is a top plan view of the construction illustrated in Fig. 1. Fig. 4 is a detail transverse sectional view taken upon the line *x* *x*, Fig. 1, and looking in the direction of the appended arrow. Fig. 5 is a side elevation of a modified form of a detail of the construction. Fig. 6 is a detail longitudinal sectional view of a modified form of construction. Fig. 7 is a similar view of a still further modified form of construction, and Fig. 8 is a similar view of a still further modified form of construction.

Referring with particularity to the drawings and to Figs. 1 to 5, inclusive, of the same, 1 designates the improved push-button, which comprises a body member 2, in connection with which the circuit-wires 3 3 are clamped and secured in position by suitable securing means 4 for direct engagement by circuit-closing means 5. In the preferred form of construction the body member 2 consists of a cylindrical interiorly-threaded shell 6, which

is provided at opposite sides with transverse openings 7, through which the circuit-wires 3 3 are passed and extended to span the interior of the shell 6 in parallel spaced relation. The walls of the shell 6 are exteriorly longitudinally grooved, as at 8, at one end of the same to receive the circuit-wires 3 3, which latter are bent, as at 9, into position to lie within said grooves 8 flush with the outer surface of the shell 6. The securing means 4 consist of an exteriorly-threaded plug 10, which is screwed into an end of the shell 6 into close engagement with the circuit-wires 3 3, and thus maintains the same positively in position for electrical engagement by the circuit-closing means 5. The circuit-closing means 5 consist in the preferred form of construction of a finger-piece 11, which carries a metallic contact-head 12 by means of a stem 13, the contact-head 12 being normally maintained out of engagement with the circuit-wires 3 3 by suitable tensional means 14, consisting of a spring coiled around the stem 13 between the finger-piece 11 and a suitable step 15 for said spring. The step 15 is provided with an axial opening 16, through which the stem 13 passes with a free slidable relation, and said step 15 is embodied in a cylindrical exteriorly-threaded shell 17, which is screwed into the end of the shell 6 opposite that which receives the plug 10, said shell 17 being provided with an enlarged cup-shaped outer end portion 18, in which is slidably mounted the finger-piece 11 of the circuit-closing means 5. Said enlarged outer end portion of the shell 17 embodies an annular abutment which limits the inward play of the finger-piece 11 and the contact-head 12, the outward movements of such parts being limited by the engagement of the contact-head 12 with the step 15. The circuit-closing means 5 and the securing means 4 are thus arranged at opposite ends of the body member of the device, and the circuit-wires 3 3, properly bared for electrical contact, are firmly held in position between the same. The body member 2 and securing means 4 and the parts of the circuit-closing means 5, irrespective of the contact-head 12, stem 13, and spring 14, are of insulating material.

In place of the openings 7 in the shell 6 I may, as illustrated in Fig. 5, provide transverse oblique lateral openings 19, through which the circuit-wires 3 3 may be passed laterally into the shell 6 instead of longitudinally, as above described.

In the modified form of construction illustrated in Fig. 6 the shell 6 is provided with a flaring base-flange 20 at the end portion of the same which receives the plug 10, which base-flange is adapted to be supported upon the base or inner wall 21^a of a box or casing 21 by suitable securing means 22. The box or casing 21 is designed to be installed within a wall or similar structure 21^b, and the outer or open end portion 21^c of the box or casing 21, through which the push-button device is inserted, is closed by an annular cap 23, which surrounds the enlarged cup-shaped outer end portion 18 of the shell 17 and is maintained in engagement with the wall 21^b by means of an annular exterior flange 24, formed upon said outer end portion 18 of the shell 17, when said shell 17 is screwed into the shell 6. This form of construction adapts the improvements to inclosed installation.

In the modified form of construction illustrated in Fig. 7 the general construction is the same as that previously described, with the exception that the securing means 25 for the circuit-wires 3 3 are exterior of the body member 2 and consist of a lock-nut 26, threaded exteriorly upon the shell 6 of the body member 2 and provided with an insulating face portion or washer 27, adapted to be screwed down on the circuit-wires 3 3 and to firmly bind the same in position against an annular exterior base-flange 28, formed upon the shell 6, the adjacent end portion of said shell 6, or that opposite the circuit-closing means 5, being closed, as at 29, to firmly support the circuit-wires 3 3 when the same are engaged by the contact-head 12.

In the constructions shown in Figs. 6 and 7 the shells 6 and 17 and parts of the securing means 4 and 25, respectively, are properly formed with respect to insulation of the circuit-wires 3 3 and the contact-head 12.

In the modified form of construction illustrated in Fig. 8 the body member 30 is associated with the circuit-closing means 33 in a manner slightly dissimilar to that above described, said body member consisting of a shell 31, of hard rubber, porcelain, or other insulating material, which is interiorly threaded at one end, as at 32, to receive the securing means 4 for the circuit-wires, said securing means consisting of the above-described exteriorly threaded plug 10. The circuit-wires 3 3 are fed through the shell 31 through suitable openings 8 in parallel relation. The circuit-closing means 33 embody a spun metallic shell 34, which is crimped at its inner or lower end, as at 35, into exterior engage-

ment with the shell 31. Within the shell 31 65 is formed a transverse step 36 for the coil-spring 14, which surrounds the stem 13 of the contact-head 12, which latter is arranged beneath or inward of the step 36, the stem 13 passing slidably through a suitable opening in said step 36. The stem 13 is provided at its upper or outer end with the usual finger-piece 11.

The operation and advantages of my improvements in push-buttons will be readily understood. Referring to Figs. 1 and 6, inclusive, the circuit-wires 3 3 are in assembling lead through openings 7 in the shell 6 and held firmly in position by the plug 10. When the finger-piece 11 is depressed against the spring 14, the contact-head 12 engages the circuit-wires 3 3 and causes an electrical circuit directly through the same. The use of separate and distinct contact-pieces, terminals, or binding-posts for the circuit-wires is thus obviated, and the body member 2 of the device, together with the securing means 4 and the circuit-closing means 5, constitute a complete, simple, and thoroughly efficient device in which the operations of wiring and electrical connection and disconnection are extremely simple.

The operation and method of use of the modified form of construction illustrated in Fig. 7 are substantially identical with those above described, the exception being that the securing means 25 are arranged exteriorly of the body member 2 and the body member 2 is formed to directly support the circuit-wires at the closed bottom portion 29 of the same.

The operation and method of use of the modified form of construction illustrated in Fig. 8 are substantially identical with those above described; but said form of construction is superior in point of inexpensiveness in manufacture and convenience in assembling parts.

Having thus described my invention, I claim and desire to secure by Letters Patent—

1. An improved device of the class described, comprising a tubular body member provided at opposite sides with transverse openings, adapted to receive circuit-wires extending through said body member, securing means fitting within one end of said body member and engaging with said circuit-wires, and circuit-closing means fitting within the other end of said body member and arranged for direct engagement with said circuit-wires to close an electrical circuit through the same.

2. An improved device of the class described, comprising a tubular body member provided at opposite sides with transverse openings adapted to receive circuit-wires extending through said body member, said body member being closed at one end and provided at the other end with circuit-closing means arranged for direct engagement with said cir-

cuit-wires to close an electrical circuit through the same:

3. An improved device of the class described, comprising a tubular body member formed to receive circuit-wires transversely and interiorly, said body member being provided at one end with circuit-closing means arranged for direct engagement with said cir-

cuit-wires to close an electrical circuit through the same. 10

In testimony whereof I have signed my name in the presence of the subscribing witnesses.

CHARLES J. KLEIN.
